UNITED STATES PATENT OFFICE.

WILLIAM WISE, OF BAY CITY, MICHIGAN.

VALVE FOR ENGINES.

SPECIFICATION forming part of Letters Patent No. 269,148, dated December 12, 1882.

Application filed August 12, 1882. (No model.)

To all whom it may concern:

Be it known that I, WILLIAM WISE, of Bay City, in the county of Bay and State of Michigan, have invented a new and useful Improvement in Valves, of which the following is a specification.

My invention relates to a valve for controlling the admission of steam to a pair of steam-cylinders for swinging the crane of an excavating-machine; and it consists, first, of a valve so constructed as to be capable of admitting steam to one steam-port in the valve-chest while exhausting steam from the other steam-port, or of simultaneously opening or closing both steam-ports; second, in combining with a valve constructed as above a cut-off valve operated directly from the main valve.

Figure 1 is a plan view of the cylinders and the connection of the valve therewith. Fig. 2 is an end elevation of the valve. Figs. 3 and 4 are respectively vertical longitudinal and cross sections through the valve.

My invention is constructed and operates as follows:

25 A B is a double circular valve-chest containing the two rocking valves D E.

C is a steam-inlet to valve-chest A, and F is a steam-port connecting the interior of valve-chests A and B, and opened or closed by moving valve D.

G G' are steam-ports communicating with cylinders O O', and H is an exhaust-port.

S S' are the spindles which move the valves E D.

35 W W' are segmental gear-wheels, keyed onto spindles S S', so that when spindle S is rocked spindle S' is rocked also.

Valve E has cut therein two steam-passages, L L', which are of equal size with the ports G G', and are as far from each other as are said ports. Outside of said steam-passages L L' are wings K K' on valve E, and in the center of said valve is an opening, R, cut into the face of said valve, of sufficient width to cover the exhaust-port and one of the steam-ports.

45 O O' are two steam-cylinders, having therein pistons which are connected with the crane of an excavating-machine, as is more fully shown in my application for a patent for an excavating-machine filed on the same day as this application. By moving the pistons in said cylinders the crane is swung, and it is important that the ropes or chains connecting both pistons with the crane be kept tight, and

55 that the engineer be able to admit steam at

will to either cylinder to start or stop the crane, or to both cylinders with equal force to hold the crane in any desired position.

When valve E is in the position shown in Fig. 4, live steam is cut off from both cylinders; but a free passage of steam from one cylinder to the other is permitted through port G, steam-passages L L', valve-chest B, and port G', thus equalizing the steam-pressure in the cylinders, holding the pistons therein in place, and holding the crane steady. When valve E is swung to the right until wing K passes port G, valve D opens port F, steam is admitted to cylinder O and exhausted from cylinder O', and the crane is swung.

To check the motion of the crane valve E may be thrown into the position shown in Fig. 4, or may be moved far enough to admit live steam into port G', and thence into cylinder O'.

What I claim as my invention, and desire to secure by Letters Patent, is—

1. In combination with a valve-chest having two steam-ports, G G', a steam-valve, E, constructed, substantially as described, to admit steam to one steam-port in the valve-chest while exhausting steam from the other steam-port, and to simultaneously open or close both of said steam-ports, as specified.

2. In combination with the valve-chest B, having the two steam-ports G G', and interposed exhaust-port H, the valve E, constructed with the two steam-passages L L', the wings K K', and the opening R, the latter being of sufficient width to cover the exhaust-port and one of the steam-ports in the valve-chest, whereby the valve can be adjusted to admit steam to one port while exhausting from the other, and to simultaneously open or close both steam-ports, substantially as described.

3. A steam-valve which will simultaneously open both steam-ports in the valve-chest, in combination with a cut-off valve connected therewith, so as to cut off steam from the main valve when the latter opens both steam-ports.

4. The combination of valve E, having spindle S, carrying thereon segmental gear W, valve D, having spindle S', carrying segmental gear W', and valve-chests A B, connected by the steam-port F, substantially as herein shown and described.

WILLIAM WISE.
